UNITED STATES PATENT OFFICE.

ADOLPH ROSNER, OF BRIDGEPORT, CONNECTICUT, ASSIGNOR TO THE LOCOMOBILE COMPANY OF AMERICA, OF BRIDGEPORT, CONNECTICUT, A CORPORATION OF WEST VIRGINIA.

INTERNAL-COMBUSTION ENGINE.

1,100,915.

Specification of Letters Patent. Patented June 23, 1914.

Application filed April 5, 1911. Serial No. 619,036.

To all whom it may concern:

Be it known that I, ADOLPH ROSNER, a subject of the Emperor of Austria-Hungary, and a resident of Bridgeport, county of Fair-
field, State of Connecticut, (whose post-
office address is 1166 Kossuth street, Bridge-
port, Connecticut,) have invented an Im-
provement in Internal-Combustion En-
gines, of which the following description,
10 in connection with the accompanying draw-
ings, is a specification, like letters on the
drawings representing like parts.

This invention relates to internal com-
bustion engines, and particularly to the
15 means for controlling the admission of fuel
to the cylinder and the exhaust of the waste
gases therefrom.

The invention will be best understood by
reference to the following description when
20 taken in connection with the accompanying
illustration of one specific embodiment
thereof, while its scope will be more par-
ticularly pointed out in the appended
claims.

25 In the drawings: Figure 1 is a sectional
elevation taken through a cylinder of the
engine embodying one form of the invention;
Fig. 2 shows a slightly modified ar-
rangement for fixing the inner sleeve with-
30 in the outer cylinder; Fig. 3 shows another
modification; Figs. 4, 5, 6, and 7 are sim-
ilar sectional elevations of the cylinder show-
ing the piston and valve in different pos-
itions; and Fig. 8 is a section on the line 8—8
35 in Fig. 5.

Referring to the drawings and particu-
larly to the embodiment of the invention
shown in Fig. 1, the engine there illustrated
is provided with a main outer cylinder 1
40 which has the water jacket 2 and is sup-
ported upon the crank casing 3. A work-
ing piston 4 is connected by the connecting
rod 5 to the crank 6 and crank shaft 7.
The rear end of the cylinder space is closed
45 by the cylinder head 8 having the water
jacket 9 communicating with the water
jacket 2 of the cylinder and having also the
centrally arranged spark plug 10.

In the described embodiment of the in-
50 vention the cylinder 1 is provided at one
side with an admission port 11 opening from
an admission chamber 12, such port extend-
ing part way around said cylinder, the lat-

ter being provided on the opposite side with
a similar exhaust port 13 opening from the 55
exhaust chamber 14.

In the described embodiment of the inven-
tion the piston 4 works in direct sliding con-
tact with the walls of an inner sleeve or lin-
ing cylinder 15, which sleeve has ports 16 60
and 17 in fixed registration with the admis-
sion and exhaust ports 11 and 13 of the
outer cylinder and such inner sleeve or cyl-
inder is rigidly held in fixed relation to the
outer cylinder and to the cylinder head, the 65
rear or upper end of the sleeve terminating
for that purpose in a flanged wall 18 which
overlies the rear end of the outer cylinder
and is bolted fast between the outer cylin-
der and the overlying flanges of the cylin- 70
der head.

To control communication between the
ports 16 and 17 of the inner cylinder and the
ports 11 and 13 respectively in the outer
cylinder, there is provided valve means in 75
sleeve form working in an annular space
provided between the inner and outer cyl-
inders. Such sleeve-valve means herein com-
prises two separate sleeve sections 19 and 20,
the former controlling communication be- 80
tween the inlet port 11 and the working
space of the engine, and the latter control-
ling communication between the exhaust or
outlet port 13 and the working space of the
engine. While sections of different extent 85
or proportions might be employed, herein
each sleeve section is semi-circular, the edges
of one (see Fig. 8) being in sliding abut-
ment against the edges of the other. The
sleeve section 19 has a port 21, and the sec- 90
tion 20 a port 22, which are brought into
and out of registration with the admission
and exhaust ports 11 and 13, respectively,
and thereby control the admission and ex-
haust. The sleeve sections may be actuated 95
by any suitable means in timed relation to
the movements of the piston and with ref-
erence to the admission, compression, firing
and exhaust. Herein the sleeve 19 has its
forward end which projects beyond the body 100
of the cylinder 1 jointed to the connecting
rod 23, the latter being eccentrically con-
nected to a countershaft 24 driven from the
crank shaft 7 through the gears 25, 26 and
27. This driving mechanism causes one full 105
reciprocation of the sleeve for each double

reciprocation of the piston. The sleeve 20 is similarly connected through the connecting rod 28 to the countershaft 29, the latter being driven through the gears 25, 30 and 31 at a similarly reduced rate of speed, the eccentric for the two sleeves, however, being so adjusted as to give the required stroke to the sleeves and the required relation to their respective ports for all positions of the piston. Preferably, though not necessarily, there is provided a supplemental port for the exhaust and herein also a supplemental port for the admission. Herein the inner and outer cylinders are provided with exhaust ports 32 and 33, respectively, connecting with a continuation of the exhaust space 14. These ports, which are in fixed registration, are adapted to be uncovered by the piston near the end of its working stroke and may be placed in communication when the port 34 in the sleeve 20 is brought into registration therewith. On the opposite side of the cylinder there are also provided the admission ports 35 and 36 in the inner and outer cylinders, respectively, the latter communicating with a continuation of the admission space 12, these ports being placed in communication when the port 37 formed in the sleeve 19 is brought into registration therewith.

The operation of the valves will be clear from an inspection of Figs. 4 to 7. In Fig. 4 the piston is shown as having completed the exhaust stroke and about to commence the return or admission stroke. Both supplemental admission and exhaust ports are covered by the piston, the exhaust port 13 having just been closed by the sleeve 20 which is moving forward, the admission port 11 just being opened by the sleeve 19 which is moving back. As the piston moves forward the port 11 is opened wider, the sleeves assuming the position represented in Fig. 5 when the forward stroke of the piston is completed. At this point the forward supplemental ports have been exposed by the piston and the sleeve 19 has opened the forward admission port, while the supplemental exhaust port is closed by the sleeve 20. At this time the sleeve 19 has commenced to move forward again and the sleeve 20 has not quite completed its forward movement. As the piston starts to move back the rear admission port 11 is quickly closed by the valve and the piston covers the supplemental admission port, the subsequent backward movement of the piston serving to compress the mixture. The completion of the compression stroke is represented in Fig. 6. At this time all ports are closed, the sleeve 19 still continuing its forward movement while the sleeve 20 has commenced its backward movement. The charge having been fired, the piston moves on its working stroke, the completion of which

is represented in Fig. 7. At that point the sleeve 19 has commenced its backward movement, the sleeve 20 has nearly completed its backward movement and has partly opened the main exhaust port 13 and completely 70 opened the supplemental exhaust port 33 which latter is now uncovered by the piston. This results in a rapid clearing of the waste gases and on the backward movement of the piston to the position shown in Fig. 4 75 the burnt gases are completely expelled through the rear or main exhaust port 13.

Since the inner and outer cylinder and the cylinder head are bolted or otherwise held in fixed and rigid relation each to the other, the annular space or chamber in which the rear end of the sleeve works can be effectively closed and packed against the escape of gases which may pass up into such space between the sleeve and the walls of the cylinder head and through leakage therefrom reduce the working pressure of the compression pressure attainable in the cylinder. The sleeve sections, being split or separated and exposed to the internal pressure of the cylinder space, are pressed radially outward affording a tight joint at and about the ports during the compression and working strokes, thereby preventing leakage. The greater the internal pressure and the greater the necessity for a tight fitting valve, the more do these valves tend to resist a tendency to leakage. This particular tendency of the sleeve sections to expand or press outwardly against their seats 100 under the working pressure of the cylinder in conjunction with the rigid relation of the cylinder head and the two cylinders prevents all leakage in and about the ports 11 and 13 or in and about the rear of the annular valve space so that all leakage is reduced to a minimum.

It will be seen that the rear end of each sleeve works in an annular chamber between the outer cylinder walls and the reentrant walls of the cylinder head, the sleeve being in immediate contact with the walls of the outer cylinder and the walls of the inner fixed cylinder. In Fig. 2 precisely the same result is secured by constructing the inner 115 fixed sleeve or lining 38 as an integral part of the cylinder head 39 so that the rear ends of the sleeve sections 19 and 20 work in direct contact with the walls of the cylinder head. In Fig. 3 a slightly different construction is shown precisely the same conditions for the prevention of leakage however being secured by constructing the sleeve, herein designated as 40, with a lower flange 41 by means of which it is fixedly 120 placed between the outer cylinder and the crank casing. In this case the reentrant walls of the cylinder head together with the separate walls of the inner sleeve constitute 125 in effect the inner cylinder, the ports 16 and 130

17 in Fig. 1 being formed by the open space 42 which separates the inner sleeve 40 and the cylinder head.

It is obvious that the sleeve sections might 5 be operated by means of cams, although herein they are shown actuated through eccentrics.

While I have herein shown and described for purposes of illustration one specific form 10 of the invention, it is to be understood that the latter is not limited to the precise construction of features disclosed nor to the form or relative arrangements of parts nor to the particular type of engine described, 15 but that extensive modifications may be made in the illustrated embodiment of the invention without departing from the spirit thereof.

Claims:

20 1. In an internal combustion engine, the combination with an outer cylinder, an inner cylinder fixedly positioned within said outer cylinder, said cylinders having exhaust openings and also inlet openings near 25 the rear end of the working cylinder space and supplemental inlet openings near the forward end of the working cylinder space, and sleeve section valves working in the space between said inner and outer cylinders 30 and adapted to control said inlet and exhaust openings and also said supplemental openings.

2. In an internal combustion engine, the combination with an inner and an outer cylinder, a working piston in said inner cylinder, inlet openings in said cylinder near the rear of the working cylinder space, supplemental inlet openings near the forward end 35 of the working cylinder space, and a segmental slide valve working between the inner and outer cylinder and controlling the 40 passage of fuel through said openings.

3. In an internal combustion engine the

combination with a cylinder and a working piston, said cylinder having an admission 45 port near the rear end thereof and a supplemental admission port near the forward end thereof, and a sleeve valve controlling said ports.

4. In an internal combustion engine the 50 combination with a fixed inner cylinder, an outer cylinder, a working piston, inlet ports in fixed registration in inner and outer cylinders, exhaust ports also in fixed registration in said inner and outer cylinders, supplemental 55 inlet and exhaust ports for said inner and outer cylinders, and sleeve valve means controlling said ports.

5. In an internal combustion engine the 60 combination with an outer cylinder, a fixed inner cylinder within said outer cylinder, separate segmental slide valves arranged between said fixed inner and outer cylinders, admission and exhaust ports in said cylinders controlled by said valves, and a cylinder head having a flange whereby it is bolted to said outer cylinder, said fixed inner cylinder also having a flange held between the head and said outer cylinder.

6. In an internal combustion engine the 70 combination with a cylinder and a working piston, said cylinder having admission and exhaust ports near the rear of the working cylinder space, a supplemental port near the forward end of the working cylinder space, 75 and a pair of segmental slide valves controlling one the admission and the other the exhaust.

In testimony whereof, I have signed my name to this specification, in the presence of 80 two subscribing witnesses.

ADOLPH ROSNER.
